FISHING LURE

Jerry M. Pierce, 141 Barnett Circle, Memphis, Tenn.

Filed Oct. 4, 1963, Ser. No. 76,870

Term of patent 14 years

(Cl. D31—4)

FIG. 1

FIG. 3

FIG. 2

FIG. 4

FIG. 1 is a top view of a fishing lure showing my new design.

FIG. 2 is a side elevational view thereof.

FIG. 3 is a front elevational view thereof.

FIG. 4 is an enlarged sectional view taken as on the line IV—IV of FIG. 2.

The dominant features of the design reside in the portions shown in full lines.

I claim:

The ornamental design for a fishing lure, as shown and described.
